To all whom it may concern:

Be it known that I, Jack Bowdan, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear of the dress unit is conventional.

I claim:

The ornamental design for a dress ensemble, substantially as shown and described.
